INFANT'S BAND

Roy A. Wassom and Lennis M. Wassom,
Nardin, Okla.

Application July 13, 1951, Serial No. 236,492

1 Claim. (Cl. 128—167)

1

This invention relates to improvements in infants' bands such as are placed around an infant to protect its abdomen and particularly the area of its navel.

The principal object of the present invention is to provide such a band which can be more readily applied to the infant's body than bands of present construction.

Another object of the invention is to provide an infant's band which will take in more surface of the infant's body to the end that more protection is afforded.

Still another object of the invention is to provide an infant's band, which when once applied will remain definitely in position against slippage with possible chafing of the infant's skin.

A further object of the invention is to provide a band of the character stated which is of simple construction, yet durable and positive acting in use.

These and various other objects and advantages of the invention will become apparent to the reader of the following description.

In the drawings:

Figure 1 is a front elevational view of the band in applied position.

Figure 2 is a rear elevational view.

Figure 3 is a section taken substantially on line 3—3 of Figure 1.

Figure 4 is a vertical sectional view taken substantially on line 4—4 of Figure 1.

Figure 5 is a plan view of the band laid open.

Figure 6 is a fragmentary detailed sectional view taken substantially on line 6—6 of Figure 5.

Figure 7 is a perspective view of the band shown applied to an infant.

Referring to the drawings wherein like numerals designate like parts, it can be seen, that the band is formed from an elongated sheet 5 of arcuate form and this is preferably soft cotton knit jersey. The sheet 5 is of arcuate shape so as to more readily conform with the shape of the infant's body, the upper longer edge taking in the larger portion of the infant under his arms, while the lower or short edge goes around the lower portion of the abdomen of the infant.

Applied to the intermediate portion of the sheet 5 are narrow tapes 6, 7 and 8 and near the ends of the sheet are sewed or otherwise secured somewhat wider tapes 9 and 10, the tape 10 being located further inward of the adjacent end of the sheet to provide a relatively long flap 11, when compared with the resultant flap 12 at the other end of the sheet. Disposed over these flaps 11, 12 are loops 13, which are sewed to the sheet 55

2

5 by the same stitching as is used in conjunction with the securing of the tapes 9, 10.

Tie members 14, 15 have their inner ends secured to the sheet 5 by the same stitching that secures the tapes 9, 10 to the sheet 5.

Thus a structure such as is shown in Figure 5 and as described above results.

The structure is placed under the infant and drawn across his front, with the flaps 11, 12 disposed in overlapping relation. When the band is properly positioned, the tie members 14, 15 are then laced through the loops 13 as in the manner shown in Figure 1, the lacing being done to the tautness desired, then a bow-knot is tied at the top as shown in Figure 1.

Obviously this band can be easily removed from the infant's body and replaced by another when it is desired that one be laundered.

Such a band as this gives ample protection and support to the new born infant's navel against possible rupture. It conforms to the infant's shape and stays in its proper place on the body. The article is easily laundered after being unlaced and removed from the baby's body.

25 A structure as described can be used on an infant of any size.

While the foregoing description sets forth the invention in specific terms, it is to be understood that numerous changes in the shape, size and materials may be resorted to without departing 30 from the spirit and scope of the invention as claimed hereinafter.

Having described the invention what is claimed as new is:

35 A device of the character described comprising an elongated sheet having substantially parallel arcuate longitudinal edges, a pair of tapes sewed to one face of said sheet inwardly of the ends thereof and radially interconnecting said upper and lower arcuate edges, a plurality of loops sewed to each of said tapes in longitudinally spaced relation and each loop on one tape adapted to correspond with a loop upon the other tape, and a pair of tie members each secured at 40 one of its ends to one end portion of one of said tapes and each adapted to be laced through said loops.

ROY A. WASSOM.
LENNIS M. WASSOM.
